UNITED STATES PATENT OFFICE.

ADDISON NORMAN, OF DAVISVILLE, CANADA.

DESIGN FOR A RUG OR SIMILAR ARTICLE.

SPECIFICATION forming part of Design No. 33,448, dated October 23, 1900.

Application filed July 7, 1900. Serial No. 22,884. Term of patent 7 years.

To all whom it may concern:

Be it known that I, ADDISON NORMAN, residing at Davisville, in the county of York and Province of Ontario, Canada, have invented and produced a new and original Design for Rugs or Similar Articles of Manufacture, of which the following is a specification.

My present invention has for its object to produce a pleasing and striking design for rugs and similar articles of manufacture.

The accompanying drawing illustrates the design. The rug therein shown has a border formed of parallel lines or bands and between such lines a series of the conventional figure known as "fylfot" or "swastika." The lines or bands of the border and the fylfot figures are drawn or worked out in heavy lines, as compared with the lines used in the formation of the central portion of the design. The space within the border just described is divided into a number of rectangular spaces or blocks by means of diagonal lines crossing each other at right angles. The arrangement

just described results in the formation of a series of rectangular spaces or blocks parallel with each other and extending diagonally across the central portion or space of the rug. Within the alternate blocks or spaces of these rows are arranged the fylfot or swastika ornament, one in each space, as represented in the drawing. This arrangement gives a sort of checker-board appearance to the central portion of the rug.

By the term "similar articles of manufacture" as used herein I mean such articles as carpets, oil-cloths, linoleums, and wood-veneer floor-coverings.

Having described my invention, what I claim, and desire to secure by Letters Patent, is—

The design for a rug or similar article, substantially such as shown and described.

ADDISON NORMAN.
